UNITED STATES PATENT OFFICE

JULIEN BERGÉ, OF TIRLEMONT, BELGIUM, ASSIGNOR TO RAFFINERIE TIRLEMONTOISE
SOCIETE ANONYME, OF TIRLEMONT, BELGIUM, A CORPORATION

CURING MASSECUISTE

No Drawing. Application filed February 11, 1927, Serial No. 167,595, and in Germany July 24, 1926.

Green sugar or massecuite was formerly boiled, so that it left the boiling apparatus in a more or less still liquid state. It was cooled in tubs, but only to the extent so that 5 it left these tubs still in the liquid state. If the massecuite showed a tendency to lose this state, syrup or even water was added in order to maintain the mass in a sufficiently liquid condition, so that the crystals could 10 be separated from the mother liquor in centrifuges of known construction in which the centrifugal force amounted to 800 times the weight of the mass to be separated.

With the continued cooling in the cooling 15 tubs, the yield of sugar increases; it is found by experience that this is also the case if the massecuite loses the liquid state and passes over into a pasty or plastic condition. Also, the yield can be still further increased if the 20 massecuite during or after cooling is deprived of a portion of its water content, for example by evaporation or the like. A massecuite of pasty or plastic condition cannot be worked in centrifuges of known construction. Experiments have now shown that by the employment of especially high centrifugal force 25 (over 800 times the weight of the centrifuged mass) the pasty or plastic masses can be separated into sugar crystals and syrup more efficiently and purer crystals are obtained 30 than were possible with liquid massecuite and the use of centrifugal forces of usual amount.

I claim:

1. A process for increasing the yield of 35 sugar crystals from any kind of massecuite which comprises boiling the massecuite, cooling to a pasty condition, and then separating the mass into sugar crystals and syrup by means of a centrifuge, in which the centrifugal force is considerably more than 800 times the weight of the mass to be separated.

2. A process for increasing the yield of 40 sugar crystals from any kind of massecuite which comprises boiling the massecuite, cooling to a pasty condition, removing a portion of its water content, and then separating the mass into sugar crystals and syrup by means of a centrifuge operating under a high centrifugal force of at least 800 times the weight 45 of the mass to be separated.

3. A process for increasing the yield of 55 sugar crystals from any kind of massecuite which comprises boiling the massecuite, cooling to a pasty condition, removing a portion of its water content by evaporation, and then separating the mass into sugar crystals and syrup by means of a centrifuge in which the centrifugal force is considerably more than 800 times the weight of the mass to be separated.

4. A process for increasing the yield of 60 sugar crystals from massecuite which comprises increasing crystallization by bringing the massecuite to a pasty condition, and then separating the mass into sugar crystals and 65 syrup by means of a centrifuge, in which the centrifugal force is considerably more than 800 times the weight of the mass to be separated.

In testimony whereof I have affixed my 70 signature.

JULIEN BERGÉ.
